Patented Nov. 5, 1974

233,500

BALL BAT PICTURE FRAME

David A. Phillips, Box 101, Coppell, Tex. 75019

Filed Oct. 10, 1972, Ser. No. 296,127

Term of patent 14 years

Int. Cl. D6—07

U.S. Cl. D6—239

FIG. 1

FIG. 2

FIG. 1 is a top plan view of a ball bat picture frame, showing my new design; and

FIG. 2 is an edge view thereof.

I claim:

The ornamental design for a ball bat picture frame, substantially as shown.
